GEORGE PUSTKUCHEN, OF HOBOKEN, NEW JERSEY.

Letters Patent No. 64,703, dated May 14, 1867.

IMPROVED APPARATUS FOR IMPREGNATING WOOD WITH TAR AND OTHER MATERIALS.

The Schedule referred to in these Letters Patent and making part of the same.

TO ALL WHOM IT MAY CONCERN:

Be it known that I, GEORGE PUSTKUCHEN, of Hoboken, Hudson county, New Jersey, have invented a new and improved Apparatus for Impregnating Wood; and I do hereby declare that the following is a full, clear, and exact description thereof, which will enable others skilled in the art to make and use the same, reference being had to the accompanying drawings, forming part of this specification, in which—

Figure 1 represents a vertical longitudinal section of my improved apparatus.

Figure 2 is a vertical cross-section of the same.

Similar letters of reference indicate corresponding parts.

This invention relates to a machine in which railroad ties and sleepers, and any other kind of wood, can be dried and saturated with tar or any other suitable substance which will prevent the decaying of the wood. The invention consists in the arrangement and construction of a boiler, and of a sheet-metal cylinder, into which the wood is placed. The annular boiler surrounds the cylinder, and is placed upon a furnace. The steam created in the boiler is used to drive an air-pump, whereby a vacuum is created in the drying-cylinder, and the pores of the wood are opened to receive the substance with which they are to be filled. When the vacuum in the drying-cylinder is complete as it can practically be made the operation of the pump is stopped, and the tar or other impregnating substance is then let into the cylinder. It will not require the use of a press to force the tar or other substance into the pores of the wood, as the vacuum created therein will be sufficient to draw the said substance into the wood and to completely saturate the latter therewith.

A represents a foundation, built of brick or other suitable material, upon which a cylindrical steam boiler, B, is arranged. The latter is made of sheet iron or other suitable material, and within it is arranged a cylinder, C, also made of sheet metal or other suitable material. The ends of the cylinder C project beyond those of the boiler B, as shown, for the purpose of facilitating the arrangement of the pipes for introducing the composition and for removing the air and waste material from the said cylinder. The boiler B becomes an annular vessel by the introduction of the cylinder C, as is clearly shown in fig. 2. A furnace, D, is arranged in the foundation A, the smoke of which is carried off in a chimney, E. One head, F, of the cylinder C is hinged, or otherwise attached, so that that end of the cylinder can be opened for the purpose of introducing or removing the wood. After the latter has been placed into the cylinder C, the cover F is firmly secured, by means of bolts and screws, or other devices, and suitable elastic washers are used, so that the cover may close air-tight. The fire in the furnace D being started, the water in the boiler is heated, and also the air in the cylinder C; thus the moisture will be removed from the wood, as well as all those portions which may afterwards have a tendency to accelerate its decay. As soon as the moisture is sufficiently removed, or, rather, as soon as the air in the cylinder is dry enough, an air-pump, G, that is secured to the cylinder, and is operated by a small steam engine, H, which is shown by red lines in fig. 1, is set in motion, and a vacuum is created in the cylinder C, whereby the pores in the wood are opened. When the vacuum is as complete as possible the pump is stopped, and a valve, a, which is secured in a pipe, b, that connects the cylinder C with the vessel I, containing the molten tar or other material, is opened, and the tar will then rush into the cylinder and saturate the wood completely. By creating the vacuum in the cylinder I am enabled to do away with the powerful presses heretofore used for forcing the preserving material into the wood. After the wood has been thoroughly saturated it may be removed from the cylinder by opening the door F. The superfluous tar or other material can be drawn off through a pipe, c, and is returned into the vessel I.

I claim as new, and desire to secure by Letters Patent—

1. An apparatus for impregnating wood, that is made and operating substantially as herein shown and described.
2. The application of an air-pump, for the purpose of impregnating wood, when combined with the cylinder C and boiler B, substantially as and for the purpose herein shown and described.

GEORGE PUSTKUCHEN.
